UNITED STATES PATENT OFFICE.

FRANK A. HALLECK, OF MICHIGAN CITY, INDIANA, ASSIGNOR TO SULLIVAN MACHINERY COMPANY, A CORPORATION OF MASSACHUSETTS.

VALVE MECHANISM.

Application filed February 9, 1924. Serial No. 691,622.

This invention relates to valve mechanisms. It has for its object to provide an improved type of valve mechanism and more particularly an improved mechanism of the plate 5 valve type especially adapted to use on high speed compressors. A further object is to provide improved means for expediting and controlling valve action, reducing breakage, and eliminating hammering action. A still 10 further object is to provide improved means for seating the valve.

In the accompanying drawings I have shown for purposes of illustration one form which my invention may assume in practice.

15 In these drawings,—

Fig. 1 is a side elevation of a compressor cylinder partly broken away to show the location of the valve mechanism.

Fig. 2 is an enlarged transverse section of 20 the valve mechanism.

I have shown my improved type of valve mechanism for purposes of illustration as controlling flow of fluid to and from a cylinder 1 having a reciprocable piston 2 therein, 25 the valve mechanism, hereinafter described, herein forming one of a plurality of such mechanisms disposed radially about each end of the cylinder. The valve mechanism proper comprises an inlet valve mechanism 3 and an exhaust valve mechanism 4, each of 30 which includes a valve of the annular flat type, which may be either rigid or resilient as desired, together with a valve seat member and guard. These mechanisms are herein 35 coaxially disposed upon a common bolt 5 which is adapted to hold the valve mechanisms relative to each other and also with respect to the cylinder.

The exhaust valve mechanism comprises a 40 central seat or hub portion 6 and usual exhaust ports 7 disposed therein, which are adapted to be opened and closed as by a valve 8. This valve is normally held in seated position as by a plurality of coaxial transversely 45 flexed or curved springs 9 having their central portion cut away as at 10 and guided by the portion 6, and reacting against a suitable plate or guard 11 and their ends bent up along a line as shown at 12, the ends of the 50 inner spring engaging the valve 8 and the ends of the outer spring overlying said ends. The springs are formed from resilient flat sheet metal and bent so as to have a single continuous major curve. A spring of this 55 nature is adapted, when tended to be flat-

tened, to be free of distortion or twisting which is present in those types of springs which are substantially circular in outline and have a series of waves. These springs are also substantially identical, thus forming 60 mating surfaces allowing the same to be nested together so that the effect of the two springs together increases the force tending to seat the valve as compared with a single spring of the desired thickness, but does not 65 increase it to the extent that a single spring would if made in one solid piece and equal to the thickness of the two springs together. A further advantage gained by this double 70 spring is that during rapid action of the valve there will always be a film of air disposed between adjacent surfaces of the two springs and hence a cushioning effect between the two springs when the valve is seated, tending to eliminate hammering. 75

The inlet valve mechanism is shown as also comprising a central seat or hub portion 15 also mounted upon the bolt 5 and having usual inlet ports 16. These ports are covered by a usual valve 17, similar to the valve 8, but it is to be noted that I use only one spring 18, similar to the springs 9, for holding the same in position. This arises from the fact that during operation the inlet valve would of course not be subjected to sudden 80 opening and closing, for the air drawn in will be at only atmospheric pressure and hence the valve must close only against a pressure which is not great enough to produce hammering. The exhaust valve, however, is 85 opened under pressure slightly greater than the receiver pressure which is considerably greater than the atmospheric pressure and which tends to close the valve quickly, thus producing hammering action. 90

It will thus be seen that my construction has certain inherent advantages due to the use of two separate springs for seating the valve which a single spring of the same resiliency would not have. The improved result 95 that I obtain by this construction is that I can seat a high speed reciprocating or movable valve with practically no hammering action. This is apparently accomplished due to the fact that a film of air is disposed between the adjacent surfaces of the two separate springs and thus during seating action the valve tends to move so quickly that the lower spring will of course first have to 100 eliminate the air between the adjacent sur- 105

faces of the two springs before it can exert any appreciable amount of seating pressure. During this action the film of air will be gradually compressed thus producing a cushioning effect. The film of air can become disposed between these adjacent surfaces during flexing of the valve on its opening movement due to the fact that there will be a tendency for the two springs to slip relative 10 to each other and hence any minute or enlarged irregularities on the surfaces of these two springs will cause the same to be separated which will supply the necessary space within which the film of air can pass. It is 15 also possible for this film of air to be materially increased and thus the cushioning action made more effective by certain structural features in the valve springs. For instance, the bent up ends will, upon flexing 20 of the springs, tend to slide relative to each other and accordingly the bent ends of the top spring will tend to ride up on the bent end of the lower spring to thereby cause a separation of the springs and increase the 25 air space therebetween which effects a cushioning action during closing of the valve. It will thus be obvious that the cushioning effect cannot be obtained with a single spring even though it does have the same amount of 30 resiliency as the double spring. Further, it will be seen that I have accomplished such a result by an extremely inexpensive means, namely, due to the fact that I use identical yieldable means thus requiring only one style 35 of spring to be carried in stock and from which any two springs may be picked out at random and so assembled as to perform their intended functions.

While I have in this application specifically described one form which my invention 40 may assume in practice, it will be understood that this form of the same is shown for purposes of illustration and that the invention may be modified and embodied in various 45 other forms without departing from its spirit or the scope of the appended claims.

What I claim as new and desire to secure by Letters Patent is:

1. A valve mechanism comprising a member 50 forming a ported valve seat, valve means on said seat, a stop member, and seating means for said valve means interposed between the latter and said stop member comprising a plurality of identical yieldable means having surfaces contacting with each other substantially over their entire areas when said valve means is seated.

2. A valve mechanism comprising a member 60 forming a ported valve seat, valve means on said seat, a stop member, and means for seating said valve means loosely interposed between the latter and said stop member comprising a plurality of substantially identical superimposed yieldable means having surfaces contacting with each other substan-

tially over their entire areas when said valve means is seated.

3. A valve mechanism comprising a member forming a ported valve seat, valve means disposed on said seat, a stop member, and means for seating said valve means interposed between the latter and said stop member comprising a plurality of substantially identical superimposed nested spring members having a permanent flexure and having 75 mating surfaces contacting with each other substantially over their entire areas when said valve means is seated.

4. A valve mechanism comprising a member forming a ported valve seat, valve means 80 on said seat, a stop member, and seating means for said valve means interposed between the latter and said stop member comprising a plurality of substantially identical yieldable means having surfaces contacting 85 with each other substantially over their entire areas when said valve means is seated, said plurality of seating means having means whereby the same are mechanically separated during opening movement of said valve 90 means.

5. A valve mechanism comprising a member forming a ported valve seat, a valve disposed on said seat, a stop member, and means for seating said valve interposed between the latter and said stop member comprising a plurality of substantially identical superimposed transversely flexed nested yieldable members having mating surfaces contacting with each other substantially over their entire areas when said valve is seated.

6. A valve mechanism comprising a member forming a ported valve seat, a reciprocable valve disposed on said seat, a stop member, and means for seating said valve interposed between the latter and said stop member comprising a plurality of coaxially disposed nested springs having mating surfaces contacting with each other substantially over their entire areas when said valve 110 is seated, said springs having means for mechanically separating the same during opening movement of the valve.

7. A valve mechanism comprising a member forming a ported valve seat, a flat annular valve disposed on said seat, a stop member, and means for seating said valve interposed between the latter and said stop member comprising a plurality of annular flexed superimposed nested springs having mating 115 surfaces contacting with each other substantially over their entire areas when said valve is seated, said springs having means for mechanically separating the same during opening movement of the valve whereby an air cushioning effect is obtained during seating of said valve.

8. A valve mechanism comprising inlet valve structure and exhaust valve structure each of which includes a ported valve seat, 130

- and a reciprocable valve disposed thereon, stop members for each of said valves, and means for seating said valves interposed between the latter and said stop members, the 5 means for seating the exhaust valve comprising a plurality of separate yieldable seating members having mating surfaces contacting with each other over substantially their entire areas when the exhaust valve is seated, 10 while the means for seating the inlet valve comprises a lesser number of said yieldable seating members.
9. A valve mechanism comprising a ported seating member, a valve disposed on said 15 seat, a stop member, and means for seating said valve interposed between the latter and said stop member comprising a plurality of substantially identical transversely flexed springs having mating surfaces contacting 20 with each other substantially over their entire areas when the valve is seated, said springs having means whereby upon movement thereof in one direction the same will be mechanically separated.
- 25 10. A valve mechanism comprising a member forming a ported valve seat, a valve cooperating with said seat, and means for yieldably holding said valve to its seat comprising a plurality of springs having surfaces contacting with each other substantially over their entire areas when said valve is seated, said plurality of springs having means whereby the same are mechanically separated during a movement of said valve.
- 30 11. A valve mechanism comprising a ported member having a valve for controlling said ports, and means for yieldably holding said valve seated comprising a plurality of substantially identical ring-like transversely flexed nested springs, certain diametrically opposite parts of said springs having bent up portions which are adapted to cause separation of said springs upon movement thereof.
- 35 12. A valve mechanism comprising a member forming a ported valve seat, a valve disposed on said seat, a stop member, and means for seating said valve interposed between the latter and said stop member comprising a plurality of substantially identical ring-like transversely flexed nested springs having mating surfaces contacting with each other substantially over their entire areas when the valve is seated, certain diametrically opposite parts of said springs having bent up portions which are adapted to cause a separation of said springs during opening movement of said valve.
- 40 13. A valve mechanism comprising a member forming a ported valve seat, a valve disposed on said seat, a stop member, and means for seating said valve interposed between the latter and said stop member comprising a plurality of nested springs having mating surfaces contacting with each other substan-
- tially over their entire areas when the valve is seated and adapted upon opening movement of the valve to have relative sliding movement therebetween.
14. A valve mechanism comprising a member forming a ported valve seat, a stop member, a valve disposed on said seat, and yieldable means for seating said valve interposed between the latter and said stop member comprising a plurality of ring shaped transversely flexed plate springs having the ring portions thereof in alinement with each other, the adjacent surfaces of said springs contacting with each other substantially over their entire areas when the valve is seated. 70
15. A valve mechanism comprising a member forming a ported valve seat, a stop member, a valve disposed on said seat, and yieldable means for seating said valve disposed between the latter and said stop member comprising a plurality of substantially identical ring-shaped nested springs adapted to have the ring portions thereof in alinement with each other, said springs having mating surfaces contacting with each other substantially over their entire areas when the valve is seated, and means whereby said valve is adapted to have spring contact at only two locations when said valve is seated. 80
16. A valve mechanism comprising a member forming a ported valve seat, a guard, a valve disposed on said seat, and yieldable means for seating said valve interposed between the latter and said guard comprising a plurality of substantially identical spring members formed of plates having mating surfaces contacting with each other over substantially their entire areas when said valve is seated, said plates being permanently flexed to provide diametrically disposed contacts with said valve. 90
17. A valve mechanism comprising a ported seat, a guard, a valve disposed on said seat, and means for seating said valve interposed between the latter and said guard comprising a plurality of substantially identical spring members having mating surfaces contacting with each other over substantially their entire areas when said valve is seated, said spring members being transversely bowed and engaging said valve only at diametrically opposite locations. 100
18. A valve mechanism comprising a member having a ported valve seat, a valve disposed on said seat for controlling the ports therein, a guard member, and means for seating said valve loosely interposed between the latter and said guard member comprising a plurality of separate identical plate springs disposed coaxially with said valve and having surfaces contacting with each other substantially over their entire areas when said valve is seated. 110
19. A valve mechanism comprising a ported seat member, a valve disposed on said seat 130

member for controlling the ports therein, a guard member, and yieldable means for seating said valve interposed between the latter and said guard member comprising a plurality of separate plate springs having mating surfaces contacting with each other over substantially their entire areas when said valve is seated, said springs being transversely bowed and having the bent portion of the springs away from the valve, the valve making contact with the adjacent spring only at the two portions of the latter most removed from the bent portion.

20. A valve mechanism comprising a ported seat member, a valve disposed on said seat member for controlling the ports therein, a guard member, and yieldable means for seating said valve interposed between the latter and said guard member comprising a plurality of identical separate nested springs each of substantially circular outline and having a substantially circular opening in the center thereof and bowed to present contacting portions in two parallel planes disposed at right angles to the axis of the spring, certain of said portions engaging said guard member.

21. A valve mechanism comprising a ported valve seat member, a valve disposed on said seat member for controlling the ports therein, and means for yieldably holding said valve to its seat comprising a plurality of substantially identical transversely flexed mutually contacting springs having means whereby during opening movement of said valve said springs are mechanically separated.

22. A valve mechanism comprising a ported seat member, a valve disposed on said seat member for controlling the ports therein, a guard member, and yieldable means for seating said valve interposed between the latter and said guard member comprising a plurality of separate plate springs provided each with a central opening and having mating surfaces contacting with each other over substantially their entire areas when said valve is seated, said springs being transversely bowed and having the bent portion of the springs away from the valve, the valve making contact with the adjacent spring only at the two portions of the latter most removed from the bent portion.

23. A valve mechanism comprising a ported seat member, a valve disposed on said seat member for controlling the ports therein, a guard member, and yieldable means for seating said valve interposed between the latter and said guard member comprising a plurality of separate plate springs of substantially circular outline, each provided with a central opening and having mating surfaces contacting with each other over substantially their entire areas when said valve is seated, said springs being transversely bowed and having the bent portion of the springs away from the valve, the valve making contact with the adjacent spring only at the two portions of the latter most removed from the bent portion.

In testimony whereof I affix my signature.
FRANK A. HALLECK.
